FIG.1

FIG.2

FIG.3

FIG.4

FIG.5

FIG.6

FIG. 1 is a top plan view of a floating thermometer showing my new design;

FIG. 2 is a side elevational view thereof;

FIG. 3 is a front elevational view thereof;

FIG. 4 is a rear elevational view thereof;

FIG. 5 is a front perspective view thereof; and

FIG. 6 is a bottom view.

The broken lines of the figures represent a conventional thermometer tube on the front and a conventional thermometer scale on the rear, the dominant features of the thermometer residing in the full line portions thereof.

I claim:

The ornamental design for a floating thermometer, as shown and described.
